DESIGN FOR A GAME APPARATUS

Lloyd B. Elliott, San Francisco, Calif.

Application January 25, 1935, Serial No. 55,042

Term of patent 3½ years

To all whom it may concern:

Be it known that I, Lloyd B. Elliott, a citizen of the United States of America, residing at San Francisco, in the county of San Francisco and State of California, have invented a new, original, and ornamental Design for a Game Apparatus, of which the following is a specification, reference being had to the accompanying drawing, forming a part thereof.

The figure is a perspective view of a game apparatus, showing my new design. The undisclosed outer side and end surfaces are plain like that shown.

I claim:—

The ornamental design for a game apparatus, substantially as shown and described.

LLOYD B. ELLIOTT.
